GEORG WIENHOLTZ, OF ESSEN, GERMANY, ASSIGNOR TO FRIED. KRUPP AKTIEN-
GESELLSCHAFT, OF ESSEN-ON-THE-RUHR, GERMANY.

TIPPING LORRY.

Application filed August 15, 1922. Serial No. 582,041.

To all whom it may concern:

Be it known that I, GEORG WIENHOLTZ, residing at Essen, Germany, a citizen of the German Republic, have invented a certain new and useful Improvement in Tipping Lorries, of which the following is a specification.

The invention relates to lorries having a tipping body and particularly to those lorries of this kind the body of which is pivotally connected to levers which are swingingly mounted on the underframe of the lorry and which body is adapted to be tipped, with respect to the said levers, by means of a tipping device, and to be lifted at the same time. The object of the invention is to so improve lorries of this kind that they can be used like an ordinary end tipping lorry.

The drawings show an embodiment of the subject-matter of the invention,

Fig. 1 is an elevation of the lorry with the body in travelling position,

Fig. 2 is the corresponding top view with the body removed,

Fig. 3 shows an elevation of the lorry with the body lifted and tipped and in a position with respect to a railway car such as to enable the material loaded to slide over from the motor lorry to said car; further, in an enlarged scale,

Fig. 4 shows a section on line 4—4 of Fig. 2, seen from the left,

Fig. 5 a section on line 5—5 of Fig. 4, and Fig. 6 a section on line 6—6 of Fig. 4.

Referring now to these drawings, A denotes the two side girders of the underframe, each of which has mounted on it a bracket a^2 (Figs. 1 to 3), a two-armed lever $B B^1$ being pivoted in each bracket a^2 by means of coaxial pins b^2 . The levers $B B^1$ are arranged symmetrically with respect to the vertical middle plane of the lorry. To the free end of the arm B^1 of the levers $B B^1$ is hinged, by pins b^3 , the rear end of side girders which form part of a frame c^1 fixed to the body C of the lorry so that the body can be tipped, with respect to the levers $B B^1$, about the axis of the pins b^3 . When in the travelling position, the body rests upon the levers $B B^1$, by means of cross beams of the frame c^1 , while the levers $B B^1$ in their turn rest upon angle pieces a^1 mounted on the rear end of the side girders A.

A lifting jack comprising telescope screw

spindles is attached to the front wall of the body C, this lifting jack being disposed in the vertical middle plane of the lorry. D^1 , D^2 , D^3 designate the screw spindles (Fig. 3) and D the lifting nut which is swingingly fixed on the body C.

The spindle D^1 rests upon a ball journal e^2 by means of a base piece d^4 having a corresponding pan (Figs. 4 and 5), a bolt d^5 connecting the base piece d^4 to the journal e^2 and having clearance in the latter. The journal e^2 forms part of a shaft e^1 which carries a bevel wheel E and is mounted on a cross beam F of the underframe by means of the hub of a spur wheel M. The bevel wheel E is in mesh with two bevel wheels G G¹ the shaft g^2 of which rests in two bearings f^1 . These bearings are mounted on a casing f^2 fixed to the cross beam F. On the hubs g^3 , g^4 of the bevel wheels G G¹ are fixed a spur wheel H and a spur wheel H¹, respectively. The wheel H is in mesh with a spur wheel J and the wheel H¹ with a spur wheel J¹. The hubs i^2 i^3 of the spur wheels J and J¹ each rest in bearings f^4 closed by covers f^3 . The inner cylindrical surface of the hubs i^2 and i^3 is provided each with a rim of teeth i^4 and i^5 , respectively.

In the bearings f^3 f^4 there is further rotatably and shiftably mounted a coupling shaft K which passes through the hubs i^2 i^3 and is coaxial with an intermediate shaft L¹ (Figs. 1 and 3) forming a connection to the shaft of the motor of the lorry. The rear end of the shaft L¹ forms a pinion L² and extends into the coupling shaft K. The latter carries at its ends external rims of teeth k¹ k² intended to be engaged by the teeth i^4 , i^5 of the wheel hubs i^2 , i^3 . Further, the inner cylindrical surface of the shaft K shows two rims of teeth k³, k⁴ which are intended to be engaged by the pinion L² of the shaft L¹. The distance apart of the rims of teeth k³, k⁴ is larger than the width of the pinion L² so that this pinion, with an intermediate position of the shaft K, will engage neither the teeth k³ nor the teeth k⁴. With the shaft K in this intermediate position, the teeth k¹ are out of engagement with the teeth i^4 and the teeth k² with the teeth i^5 . By shifting the coupling shaft K, however, out of this position in the direction of arrow x (Fig. 5) the teeth k⁴ can be caused to engage the pinion L² and the teeth k² to engage the teeth i^5 .

so that the body C can be tipped by the motor of the lorry about the axis of the pins b^3 into the discharging position, and this through the intermediary of the members 5 L^1 , L^2 , K , J^1 , H^1 , G^1 , E , e^1 , d^3 and the lifting jack D D^1 D^2 D^3 .

A shifting of the coupling shaft K in the direction opposite to arrow x will cause the rim of teeth k^3 to engage the pinion L^2 and 10 the teeth k^1 to engage the teeth i^4 , thus causing the tipping gear to be reversed and the body C to be lowered again into the travelling position by the motor. The shifting of the shaft K is performed by means of a lever 15 Z (see particularly Fig. 4) mounted on the casing f^2 which lever embraces the shaft K with a circular portion and engages in an annular groove of the shaft by pins Z^1 .

The spur wheel M, mounted on the shaft 20 e^1 of the bevel wheel E, engages in two spur wheels N (Fig. 4) which are disposed symmetrically with respect to the vertical middle plane of the lorry. Each of these spur wheels N is rotatably mounted on the hub 25 p^1 of a spur wheel P which, in its turn, is mounted on a journal p^2 fixed on the cross beam F. The hub n^1 of each spur wheel N upwardly extends through a bearing n^2 which is supported by a plate f^5 fixed on the 30 cross beam F. The upper front faces of the hubs n^1 , p^1 of the wheels N and P show coupling teeth n^3 and p^3 , respectively. On each journal p^2 there is further rotatably and shiftable mounted a coupling member Q (see also Fig. 6) having corresponding coupling teeth q^1 and acted upon by a spring q^2 one end of which rests on the coupling member Q while the other end bears against a disc q^3 fixed by a nut q^4 screwed on the 35 journal p^2 . The spring q^2 tends to hold the coupling member Q in a position such as to cause the coupling teeth q^1 to engage the teeth n^3 and p^3 , the coupling member Q thus rigidly connecting the spur wheel N to the 40 spur wheel P. Each coupling member Q shows an annular groove q^5 in which engage two pins r^2 fixed to two fork levers R. The fork levers R of the two coupling members are fixed on a shaft r^3 (see particularly Fig. 45 6) which rests in bearings f^6 fixed on the plate f^5 of the cross beam F. A hand lever R^1 fixed on the shaft r^3 serves to oscillate the fork levers R in a manner such as to cause the coupling members Q to be shifted, 50 against the action of the springs q^2 , along the journals p^2 and the coupling teeth q^1 thus to come out of engagement with the coupling teeth n^3 and p^3 . On the driver's cabin is provided a guide arc a^3 by means of 55 which the hand lever R^1 can be locked in two positions (I and II, Fig. 6) in which the teeth q^1 of the coupling member Q are in or out of engagement with the teeth n^3 and p^3 .

60 A pawl f^9 (Fig. 6) is pivotally mounted

in eyes f^7 on the plate f^5 , by means of a pin f^8 , said pawl having a projection f^{10} which is adapted to engage either above or below a projection r^5 of one of the fork levers R, according to the position of the hand lever R^1 . The pawl f^9 shows further an arm f^{11} against which abuts a projection c^2 fixed to the front end of the body C, when the body takes the travelling position. Within the pawl f^9 there is shiftable mounted a bolt f^{12} 75 which is under the action of a spring f^{13} and abuts against the plate f^5 .

Each of the spur wheels P is in engagement with a spur wheel S (Fig. 4) which is rigidly fixed on a screw spindle T. These 80 screw spindles are rotatably but non-shiftably mounted on the underframe of the lorry, they pass each through a bearing t^1 and rest, on the one hand, by a collar t^2 upon the lower front face of the bearing t^1 , through the intermediary of a ball bearing t^3 , and, on the other hand, upon the hub s^1 of the spur wheel S, by means of a nut s^3 screwed on said spindles and fixed thereto by a pin s^2 , said hub s^1 , in its turn, resting upon 90 the upper front face of the bearing t^1 . The screw spindles T, T are held at their upper ends each in a bracket a^4 fixed on the driver's cabin and are engaged by female threads of a traverse U. The ends of this traverse U are connected each by a rod V with the free end of the arm B of the respective double-lever B B¹. Owing to this arrangement it is possible, by means of the motor of the 100 lorry, not only to operate the lifting jack D, D¹, D², D³ but also, with the coupling members Q thrown in, to so shift the traverse U on the screw spindles T that, through the intermediary of the rods V and the levers B B¹ swinging about the axis of the pivots b^2 , the body C is simultaneously lifted when 105 it is tipped into the discharging position.

The body C shows a downwardly tiltable rear wall c^3 (Figs. 1 and 3) to which are fixed two side plates c^4 guided on the side 110 walls of the body. An arm W (Figs. 1 to 3) is rigidly connected to the rear end of the body C and has hinged on it a rod w^1 the other end of which is connected by a pin w^2 to an arm w^6 pivotally mounted on one of 115 the pivots b^2 . To the pin w^2 is attached a rod w^3 hinged to a rod w^4 . The latter is guided in a bearing w^5 fixed to the underframe of the lorry, and has a slot w^7 through which projects the above-described lever Z 120 operating the coupling shaft K. The system of rods W w^1 , w^2 , w^3 , w^4 , w^6 , w^7 is capable to so adjust the lever Z, when the body C is in its extreme tipping positions or in 125 travelling position, that the coupling shaft K comes to be thrown out.

In case the body C has to be tipped into the discharging position as an ordinary end tipping lorry, the hand lever R^1 has to be 130 brought into the position II (Fig. 6) and to

be locked in this position. The coupling members Q are then out of engagement. Thereupon the coupling shaft K is shifted, by means of the lever Z from the middle position in the direction of arrow α (Fig. 5). With the motor running, the body C is now tipped about the axis of the pivots b^3 . Immediately after the beginning of this tipping movement the projection c^2 comes to be lifted from the arm f^{11} of the pawl f^9 which latter will thereupon be swung, by the spring-operated bolt f^{12} into a position such as to cause the projection f^{10} to engage under the projection r^5 of the fork lever R. The hand lever R^1 is thus hindered to be brought into position I so that the teeth q^1 of the coupling members Q cannot engage the teeth n^3 and p^3 of the spur wheels N and P, while the body is tipping. During the tipping movement the body C so acts upon the lever Z, by means of the rod system W, w^1 w^2 , w^3 , w^4 , w^6 , w^7 , that, with the extreme tipping position of the body C, the coupling shaft comes to take again its middle position and thus to be thrown out of operation.

If the body C has to be lowered again into the travelling position, the coupling shaft K has to be shifted opposite to arrow α by means of the lever Z. When the body attains the travelling position, the rod system W w^7 throws the coupling shaft K out of operation by means of the lever Z. At the same time the projection c^2 shifts the pawl f^9 into the position of Fig. 6 so that the fork lever R is released again by the latter.

If the body C has to be tipped and lifted up to the position of Fig. 3, for example, in order to directly transfer the loaded material from the motor lorry into another vehicle, a railway wagon for example, the hand lever R^1 has to be brought into position I. The teeth q^1 of the coupling members Q then are in mesh with the teeth n^3 and p^3 of the spur wheels N and P. If now the coupling shaft K is shifted in the direction of arrow α , the body will be tipped about the axis of the pivot b^3 and at the same time lifted by the members e^1 , M, N, Q, P, S, T, U, V, B B^1 . At the beginning of this tipping and lifting the projection c^2 releases the pawl f^9 so that the projection f^{10} of the latter engages over the projection r^5 of the fork lever R in question. Thus the coupling members Q are secured against disengagement during tipping and lifting the body C. When this latter has reached its extreme tipping position, the coupling shaft K comes to be thrown out by the system W to w^7 . The transferring of the tipped and lifted body C is initiated, as in the first described case, by shifting the coupling shaft K in the direction opposite to arrow α . When the body comes to

reach again the travelling position, the coupling shaft is thrown out again as above described, and the fork lever R is released anew by the pawl f^9 .

Claims:

1. A lorry comprising an underframe and a body, levers pivotally connected to said underframe, said body being pivotally connected to said levers, means for tipping said body with respect to said levers, means for swinging said levers in order to lift the body, and a coupling arrangement between said levers and said means for tipping said body, said coupling being arranged to allow movement only of said tipping means or of said tipping means and said levers conjunctively.

2. A lorry comprising an underframe and a body, two-armed levers pivotally connected to said underframe, one end of said body being pivotally connected to an arm of each of said levers, means for tipping said body with respect to said levers and means for swinging said levers in order to lift the body, said tipping means being operable independently of or conjunctively with said swinging means.

3. A lorry comprising an underframe and a body, levers pivotally connected to said underframe, said body being pivotally connected to said levers, a source of power, means actuated through said source of power for tipping said body with respect to said levers and for swinging said levers in order to lift the body, a member adapted to couple said actuating means to said levers, means for locking said coupling member at the commencement of the tipping movement and of the lifting movement of said body and for automatically releasing said coupling member at the return of said body into the travelling position.

4. A lorry comprising an underframe and a body, two-armed levers pivotally connected to said underframe, one end of said body being pivotally connected to an arm of each of said levers, a source of power, means actuated through said source of power for tipping said body with respect to said levers and for swinging said levers in order to lift the body, a member adapted to couple said actuating means to said levers, means for locking said coupling member at the commencement of the tipping movement and of the lifting movement of said body and for automatically releasing said coupling member at the return of said body into the travelling position.

The foregoing specification signed at Essen, Germany, this 18th day of July, 1922.

GEORG WIENHOLTZ.
